UNITED STATES PATENT OFFICE.

RALPH C. GARLAND, OF DETROIT, MICHIGAN, ASSIGNOR TO SKINNER AUTOMOTIVE DEVICE CO., INC., OF DETROIT, MICHIGAN, A CORPORATION OF CALIFORNIA.

LUBRICATION OF INTERNAL-COMBUSTION ENGINES.

Application filed September 13, 1926. Serial No. 134,958.

In withdrawing fluids, especially impure or polluted lubricating-oil, from around the pistons of internal-combustion engines in order that its rectification and return to the 5 lubrication system of the engine for further use may be effected, it has been found that the conduit or passage through which such oil is abstracted from the piston may be left open or uncovered temporarily for 10 a small portion of the time, by reason of the reciprocation of the piston, without substantially disturbing or deranging the engine carburetion, even when the source of suction for such oil-withdrawal is the partial 15 vacuum present in the intake-manifold of the engine, provided a suitable, small or metered hole or passage is present in the piping system, preferably near the piston, to limit the amount of air which can be 20 drawn into the intake-manifold therethrough.

In the development of constructions of this character, especially for the sleeve or Knight type of engines, several advantages, 25 structural, functional, and manufacturing, were found to accrue from the style and form of mechanism constituting the subject-matter of the present invention.

In an appliance of this character, it is desirable 30 to have the small or limiting hole or passage near the piston, but with a relatively large cavity or mouth for the accumulation of oil, so that when the hole or passage is uncovered, owing to its small 35 size, it will, for a time, be somewhat clogged, or at least partially closed, by the oil, accumulated in the adjacent, larger mouth or recess, flowing therethrough in a restricted manner.

In order that those acquainted with this 40 art may fully understand the present invention in its several aspects, a present, desirable embodiment of the same has been depicted in the accompanying drawing, 45 throughout the views of which like reference characters have been used for the same parts.

In this drawing,—

Fig. 1 is a fragmentary, vertical, central 50 section through one cylinder of a multi-cylinder engine of the Knight type incorporating the present improvements; and

Fig. 2 is an elevation of a small portion

of the outer surface of the inner, reciprocatory sleeve, showing the metered passage 55 referred to above.

Turning to this drawing, it will be seen that the engine or motor comprises the customary, water-jacketed cylinder 12 having the usual inlet and exhaust ports 13 and 14, 60 a reciprocating piston 15, its connecting-rod 16, an inner, sliding sleeve 17, and an outer, reciprocating sleeve 18, both sleeves being located between the piston and the cylinder, as is common practice, and both being provided with ports co-operating, as is usual, with the intake and discharge ports of the cylinder.

The cylinder, sleeves and piston are lubricated in any approved away, as by oil 70 splashed on them by the movements of the connecting-rod co-operating with a supply of oil in the lower part of the crank-case 19, of which only a small section of the upper portion is shown.

A properly-located port 21, through the cylinder side-wall directly below the inlet port 13, is in communication with a horizontal, flattened, tubular manifold 22 positioned alongside of, and similarly operatively connected to, the other cylinders of the multi-cylinder engine, such manifold being joined to an oil rectifier (not shown), in which the withdrawn, polluted oil is purified, and from which the rectified oil is 85 returned to the crank-case for further use, the rectifier being connected to the intake-manifold of the engine as a source of suction to withdraw the impure oil from the engine and deliver it into the rectifier and to facilitate the vaporization therein of contaminating ingredients.

Inasmuch as such rectifiers, their associations with the other parts of the mechanism, and their manner of functioning, are well 90 understood in the art, it has not been deemed necessary to illustrate this portion of the appliance, the invention relating more particularly to the construction of the inner sleeve.

The outer, sliding sleeve 18 has a port 23 therethrough in register with and in constant communication with the cylinder-port 21 and with a long groove 24 cut in and disposed lengthwise of the outer surface of the 105 inner sleeve, the lower end of such channel

24, by means of a small, shallower, metered groove or channel 25, connecting with a port 26 through the inner sleeve, such latter port at intervals being in register with an oil-collecting groove 27 extending around the outside of the upper portion of the piston between piston rings of the latter, and having an air-inlet port 28 connected therewith directly opposite the port 26 and extending through the piston-wall to its hollow, interior chamber, which, of course, is always in open connection with the upper part of the interior of the crank-case.

For a certain portion of the travel of the piston, its transverse groove 27, in which impure oil collects, is in communication with the inner-sleeve port 26, at which suction is always present by reason of its uninterrupted connection with the manifold 22, the sub-atmospheric pressure in which is, as has been explained, brought about by its pipe connection with the engine intake-manifold through the rectifier.

During the limited period of such register, the impure oil, aerated by air from the crank-case entering the groove through the bleeder port 28, is withdrawn or abstracted from the piston-groove through the connections 26, 25, 24, 23 and 21, to the manifold 22, from which it is sucked or drawn into, and purified in, the rectifier, and then returned, either intermittently or continuously, to the crank-case, the separated air, vapors and gasified, polluting ingredients passing into the engine through the intake-manifold, where they are consumed with the gaseous-mixture fuel.

During a portion of the sliding travel of the piston, the sleeve-port 26 is closed by the piston-skirt, and, for a part of the time, upon further ascent of the piston, the port will be unclosed or uncovered, and it is during this period that the metered channel 25 performs its particularly valuable and efficient function.

While the piston is moving, a certain amount of oil collects in the port 26, which, during that period, is covered by the skirt of the piston, so that the vacuum is unbroken.

When such piston-skirt rises above the sleeve-port, the vacuum is relieved, and the accumulated oil and air are drawn or sucked through the small channel 25 into the rectifier, but such passage, because of its small and restricted cross-section, presents so much resistance to the flow of the oil therethrough, that but comparatively little air enters the system before the sleeve-port is again closed by the piston, and the amount of air thus drawn into the intake-manifold has no substantial, detrimental effect on the carburetion.

The invention is not restricted to the exact construction illustrated and described in

detail, and several, minor, mechanical changes may be made therein without departing from the invention as defined by the following claims and without the loss of any of its material benefits.

I claim:

1. In an internal-combustion engine, the combination of an engine-cylinder having a port through its side-wall, a piston having an oil-collecting groove reciprocatory in said cylinder, a movable sleeve between said piston and cylinder, means to lubricate said cylinder, piston and sleeve, said sleeve having a longitudinal groove of substantial size in its surface adapted to communicate with said cylinder-port, a port through the sleeve adapted to register at least part of the time with said piston-groove, and a small-metered channel connecting said longitudinal sleeve groove and said sleeve port, whereby the contents of said piston-groove may be removed through said cylinder-port.

2. In an internal-combustion engine, the combination of an engine-cylinder having a transverse oil-collecting groove reciprocatory in said cylinder, a movable sleeve between said piston and cylinder, means to lubricate said cylinder, piston and sleeve, said sleeve having an external longitudinal groove of substantial size in its outer surface adapted to communicate with said cylinder-port, a port through said sleeve below said longitudinal groove and adapted to register at least part of the time with said piston-groove, and a small-metered channel on the outer surface of the sleeve connecting said longitudinal sleeve groove with said sleeve port, whereby the contents of said piston-groove may be removed through said cylinder-port.

3. In an internal-combustion engine, the combination of an engine-cylinder having a port through its side-wall, a piston having an oil-collecting groove reciprocatory in said cylinder, an outer movable sleeve having a port therethrough registering with said cylinder-port, an inner sleeve between said outer sleeve and said piston, means to lubricate said cylinder, piston and sleeves, said inner sleeve having a longitudinal groove of substantial size on its outer surface in communication with the port through said outer sleeve, a port through said inner sleeve adapted to register at least part of the time with said piston-groove, and a small-metered channel on the outside of said inner sleeve connecting said longitudinal sleeve groove with said inner sleeve port, whereby the contents of said piston-groove may be removed through said cylinder-port.

In witness whereof I have hereunto set my hand.

RALPH C. GARLAND,
